DEVICE FOR INDICATING EXCESSIVE SPEED OF TURBINE IN TURBINE-DRIVEN VEHICLE

Leon Saives, Billancourt, France, assignor to Regie Nationale des Usines Renault, Billancourt, France, a French corporation

Application May 27, 1952, Serial No. 290,367

Claims priority, application France June 20, 1951

3 Claims. (Cl. 200—61.9)

In road or rail turbine-driven vehicles with a hydraulic or mechanical transmission the speed of the turbine increases proportionally to that of the vehicle or is a direct function thereof.

Particularly when the vehicle concerned is a locomotive, it may happen that its speed, on a steep decline, reaches a value higher than that which corresponds to the normal running of the turbine and exposes the latter to the danger of bursting.

The present invention has for its object to obviate this danger, by attaching to the turbine an indicator device which, operating when the speed becomes too high, warns the engineer, who will then take the steps necessary to avoid the danger. This indicating system may, moreover, be combined with other arrangements for automatically placing the transmission of the vehicle in the neutral position and/or causing the operation of the brakes.

The indicator system according to the invention causes essentially a switch which closes an electric circuit controlling the warning signal proper. This switch is itself actuated directly or indirectly by a movable rod. The latter is connected to the turbine, by suitable means, and set in motion as soon as the critical speed is reached.

Certain embodiments of the invention are shown, by way of non-limitative examples, in the accompanying drawings, in which:

Figure 1 shows an embodiment in which the signal is actuated by a device depending at the same time on the speed of the turbine and on the position of the control lever at the driving position;

Figure 2 shows a modification of a detail;

Figure 3 shows a modification in which the sound or other signal continues to operate even when the speed of the turbine has been reduced to a value lower than that for which the signal has been set in operation, and

Figure 4 relates to an embodiment operated electrically.

In all the figures, the operation of a suitable signal is effected by the closing of a switch by sliding movement of a rod 3.

Referring to Figure 1, there is shown a cylinder 6, the piston of which, acted on by a spring 7, is subjected to the action of air or liquid pressure depending on the speed of the turbine (this constituting an arrangement which is well known in the turbine art). This piston operates on a lever 8 pivoted at 9 and the end 10 of which acts on the end 11 of a balance member 12, the centre 13 of which controls, by a rod 3, the switch 4 which actuates a sound or other signal 5. The end 14 of the balance member 12 is controlled by a rod 15 of a piston 16 subjected to air or liquid pressure depending upon the position of the control lever at the driving position.

The members 15 and 16 may also be replaced by a rod 17, the position of which depends on that of the control lever at the driving position (Figure 2).

The switch 4 will be closed when the points 11 and

2

14 of the balance member 12 occupy the positions 11' and 14', in other words, when the speed of the turbine will be too high, the control of this speed being, on the contrary, at its throttled position 14'. This will be produced in the event of racing of the vehicle on a down grade, for example. The signal will be prevented from functioning if the speed of the turbine drops to an acceptable value.

It is naturally possible to use a centrifugal speed-responsive device instead of a pressure-type speed-responsive device such as indicated at 6 and 7 in Fig. 1.

Figure 3 shows a rod 18, the enlarged end 19 of which is actuated through a slide 20 by a rod 3 corresponding to the rod 3 of Figure 1. The slide 20 permits a pull

15 to be applied to the rod 18, but not a push.

When the signal 21 is to be actuated, the rod 3 pulls the rod 18 downwardly, the effect of which is to pull a rod 22 towards the right by means of a bell-crank lever 23. The rod 22 has a shoulder 24 urged towards the left by a spring 25. The movement of the rod 22 towards the right frees a rod 26 of a switch 27. A spring 28 tends to move the rod 26 downwardly. When the rod 26 is freed by the rod 22, the switch is closed and even if subsequently the rod 3 should move upwardly again, 25 the assembly 18—23—22 remains in position, since the end of rod 22 bears against the rod 26. It will only be possible to stop the sound signal by pulling the rod 26 upwardly by means of a button 29, which will free the rod 22.

30 Figure 4 shows an electrical arrangement giving the same result as the arrangement according to Figure 3.

The sound signal 21 is set in operation by a relay 30, the coil of which is energised by a switch 31 set in operation by the rod 3, which serves the same purpose as 35 the rods 3 of Figures 1 and 3. When the relay 30 is excited, switch blades 32 and 33 are attracted and bear against contacts 34 and 35, and the current then passes through the switch 32, 34 to the signal 21 and also through the switch 33, 35 to a terminal 36 of the relay 30, holding the latter energised even if, as a result of lowering of the speed of the turbine, the switch 32, 34 is opened.

It is then only possible to stop the signal 21 by pressing on a button 37 of a switch 38, which interrupts the current simultaneously at the switches 32, 34 and 33, 35. 45 The relay 30 then returns to its position of rest.

Without departing from the scope of the invention, it is possible to visualise other mechanical or electrical solutions for causing the displacement of the rod 3.

The signalling device which has been described may 50 be combined with a system for placing the transmission in neutral, particularly with that system which form the subject of the application of the present applicant, Serial No. 290,368, filed simultaneously with this application for means for automatically limiting the speed of 55 turbines driving vehicles by placing the transmission in the neutral position, and means for automatically limiting the speed of turbines driving vehicles by applying the brakes.

I claim:

60 1. A device for indicating excessive speed of the turbine in a turbine-driven vehicle having an operator-controlled member at the driving station, comprising means responsive to the rotational speed of the shaft of the turbine and displaceable when said shaft exceeds a predetermined speed, an electrical switch having a member movable to open and close said switch, a floating lever having a fulcrum and two arms, means connecting the fulcrum of said lever to said movable member of the switch, means connecting one arm of said lever to said speed responsive means and means connecting the other of said arms to said operator-controlled member, movement of said movable member to operate said switch being

thus effected by the resultant movement of said speed-responsive means and said operator-controlled member.

2. A device for indicating excessive speed of the turbine of a turbine-driven vehicle having an operator-controlled throttle, means responsive to the rotational speed of the shaft of the turbine and comprising a member displaceable when said shaft exceeds a predetermined speed, an electrical switch having a member movable to open and close said switch, signal means controlled by said switch, a floating lever having a fulcrum and two arms, means connecting the fulcrum of said lever to said movable member of the switch, means connecting one arm of said lever to said displaceable member of said speed responsive means, means connecting the other of said arms to said throttle, movement of said movable member to operate said switch being thus effected by the resultant action of said speed-responsive means and said throttle.

10

15

3. A device according to claim 2, in which the connection between the fulcrum of said lever and said movable member of the switch includes an actuating member connected to said fulcrum, a switch-operating member movable by said actuating member in a direction to close said switch but not in the opposite direction, means for holding said switch in closed position and operator-controlled means for releasing said holding means.
